UNITED STATES PATENT OFFICE.

CHARLES R. HANSEN, OF CEDAR RAPIDS, IOWA.

COMBINED STEAM AND HOT-AIR HEATING SYSTEM FOR BUILDINGS.

1,270,027.

Specification of Letters Patent. Patented June 18, 1918.

Application filed May 1, 1917. Serial No. 165,755.

To all whom it may concern:

Be it known that I, CHARLES R. HANSEN, a citizen of the United States, residing at Cedar Rapids, in the county of Linn and 5 State of Iowa, have invented certain new and useful Improvements in Combined Steam and Hot-Air Heating Systems for Buildings, of which the following is a specification.

This invention relates to an improvement 10 in combined sanitary steam and air heating systems for buildings, and is especially adapted for use in heating cottages, bungalows, store buildings, apartments and residences of the medium size construction including from six to eight rooms.

The main object of this invention is to provide a novel, simple, durable, economical and efficient sanitary means for heating and ventilating buildings which can be readily 20 operated by anyone who can tell when the water gets low in the water gage carried by the furnace.

Another object of the invention is to provide a heating system which includes the 25 entrance of fresh air at the floor portion of a hot air room through the hollow wall forming one side of said room, which air becomes warmed by contact with the inner wall of the room before its entrance therein, 30 the air then being highly heated, disinfected and purified by the means hereinafter described, said means being fixed and suspended in the hot air room, from which room the air is forced by suitable distributing pipes 35 and an electrically operated fan to the various rooms or apartments.

The foregoing and such other objects as may appear from the ensuing description are attained by the novel features of construction, combination, arrangement and location of the parts, hereinafter fully described, illustrated in the accompanying drawings, and particularly pointed out in the claims appended hereto, it being understood 45 that slight changes in the form, proportions, and minor details of the construction may be resorted to without departing from the spirit or sacrificing any of the advantages of the invention.

50 In the accompanying drawings, which form a part of this specification, it will be seen that:—

Figure 1, is a perspective view illustrating the improvements embodying my invention.

55 Fig. 2, is a longitudinal sectional view through an air vent of the steam radiators.

Fig. 3, is a plan view of the air moistening coil which is suspended around the steam radiator, and

Fig. 4, is a perspective view of the air disinfecting and purifying drum or tank which is suspended around the heating furnace.

Similar letters of reference are employed to designate corresponding parts throughout the several figures of the drawings.

In the embodiment of my invention as illustrated and which shows a preferred construction, A indicates the hollow wall forming one side of the hot air room B, the fresh air being led into the hollow wall through the inlet A' passes downward therein becomes warmed or partially heated in its passage by contact with the inner wall B' of the hot air room and is caused to emerge into said room through a series of openings 70 g formed in the lower or bottom portion of said inner wall B'.

Suitably located within the air room, as shown in Fig. 1, is a steam boiler furnace a adapted to radiate the heat therefrom in 80 heating the air, which heat otherwise goes to waste, and connected to said boiler furnace is a smoke flue a' which leads to a counter-heater b intended to utilize all of the heat that usually passes out of the chimney in heating the air within the air room, said counter-heater being connected with a pipe b' leading to the chimney and provided with caps d which may be removed for cleaning purposes and readily replaced. Connected to the upper portion of the boiler furnace is a water gage e and a steam gage e' which are adapted to be extended outside of the front wall so as to be visible at all times.

95 C, designates a steam heated coil which is suspended near the ceiling by rods c, c, which are rigidly but removably secured to a supporting bar h, carried by the ceiling, said coil C being connected to the upper part of the boiler, and f indicates a coil box or casing made of sheet iron suitably supported at the ceiling which casing is open at its bottom portion for the purpose of leading the air in the room to its last and final heating before 100 it is distributed to the rooms or apartments above. Located within said box or casing is a series of steam heated radiators, or section coils o adapted to further heat the air which is led into the casing by the electrically operated fan l before the heated air is forced by the said fan to the rooms or apartments 105 110

through the main distributing pipe S , said radiator sections or coils o being suitably connected with the upper part of the boiler furnace.

- 5 As shown in Fig. 1 a cast iron plate h is utilized for bridging or supporting a continuation of the brick work construction above the fire-place, and the main distributing pipe S , may be provided with any suitable number of branch pipes i , leading to the several rooms or apartments and through which the hot air from the hot air room is distributed.

10 The boiler furnace is supplied by water fed thereto through the supply pipe p connected to any suitable or desirable source of water supply, which pipe p is provided with a valve p' .

15 Within each upper head portion of the steam heated radiator sections o is a cylindrical member Y secured to said head portion, and within said member is fitted a hollow cylindrical valve z having an outlet u communicating with the air-vent U which 20 extends from each of the sections o , said valve z , being provided at one end thereof with an outwardly extending stem z' to the outer end portion of which is suitably secured an upwardly projecting arm w , as 25 shown in Fig. 2, each of the arms w being connected by a horizontally arranged bar w' , one end of the bar being connected to an operating wire or chain v leading to a suitable room or apartment, and the other 30 end of the bar being connected to a wire, cord, or chain v' , to which a weight s is attached at its outer end, whereby a slight pull on the operating wire or chain will move the horizontal bar laterally thus causing the 35 outlet in each valve to register with each air vent thereby permitting the air to be freely 40 vented and to escape from the radiator sections, and when the operating rope is released the weight will move the said bar in 45 the opposite direction thereby closing the air vents. It will be seen that the said horizontal bar w' may be provided with a notched or toothed section s' , adapted to engage with a pawl or catch t for the purpose 50 of holding the vents in open or closed position as long as desired, said catch or pawl being connected with an operating wire or chain t' .

55 In the wall of each room or apartment is suitably located a hot air inlet register n' , a cold air outlet register m communicating with the hot air room, and a foul air outlet register m' connected with a foul air flue.

60 Suitably suspended in a level horizontal position in the casing f , and surrounding the radiator section, is an air moistening or disinfecting device n , consisting of a series of pipes connected together, each pipe and its connection being perforated through its upper portion, said moistener having a funnel

shaped connection r through which the water or other liquid is fed into the said moistener, and suitably secured around the boiler furnace in any desirable position is a roundly shaped tank n^2 having a vertical inner and outer wall and provided with a series of openings in and near its upper end portion said tank being adapted to be partially filled with a disinfecting, air sweetening, or air purifying liquid which will gradually evaporate and the vapors thereof will pass through the openings in the tank, commingle and mix with the air in the hot air room and be distributed through the main conductor to the several rooms or apartments, the said liquid being supplied through the funnel r' .

65 It will be readily obvious that an electric button may be placed near the bed of the attendant in charge of the heating system who can if desired before arising press the button and thus start the electrically operated fan, thereby stirring and circulating the air in the room, and if there is any heat in the hot-air room it is immediately forced into the room, then by shaking the fire in the boiler furnace, opening the draft, and adding fresh fuel steam will soon be generated and the air will become suitably heated for its distribution throughout the building, and can be economically maintained in its heated 70 condition.

75 It will be perceived that the chill of the fresh air is removed and the air partially heated before its contact with the steam pipes thereby saving considerable steam 80 which means a saving of fuel.

85 The safety valve q connected to the top of the boiler furnace may be set at 15 lbs. since 5 lbs. of pressure is all that is usually required for a six or seven room house.

90 In cases of sickness the air may be purified, sweetened or disinfected by the use of a proper solution poured into either or both the device n , and the tank n^2 , and it will be readily seen that the system hereinbefore 95 described is an efficient one for the economical sanitary heating and ventilating of the rooms or apartments of buildings, and it is thought that the construction and operation of my improved system will be readily 100 understood without further description pertaining thereto.

105 Having thus described my invention, what I claim and desire to secure by Letters Patent is:—

110 1. A combined steam and hot air heating system comprising a hot air room provided with a hollow side wall having a series of inlets at its bottom portion for the admission of partially heated fresh air into the 115 room, a steam boiler within the room, a smoke flue heater connected to said boiler and suspended between the boiler and said wall, a steam coil heater suspended from the ceiling, a casing provided with a series of 120

125 130 135

- radiator sections suspended from the ceiling of said room, a main hot air distributing pipe connected to one end of the said casing, and a fan connected with the rear portion of the casing for forcing the heated air from said room to the several rooms of the building.
2. A combined steam and hot air heating system for buildings comprising a hot air room provided with a hollow side wall having a series of inlets at its bottom portion for the admission of partially heated fresh air into said room, a steam boiler furnace within the room, a smoke flue heater connected to said furnace and suspended between the furnace and said wall, a steam coil heater suspended from the ceiling of the room, a casing suspended from the ceiling of the room, said casing being provided with a series of steam heated radiator sections and connected with said furnace, a main hot air distributing pipe connected to one end of the casing, and a fan connected to the rear portion of the casing for forcing the heated air from the casing to the several rooms of the building.
3. A combined steam and hot air heating system for buildings comprising a hot air room provided with a hollow side wall having a series of inlets at its bottom portion for the admission of partially heated fresh air into said room, a steam boiler furnace within the room, a smoke flue heater connected to said furnace and suspended between said furnace and wall, a steam coil heater suspended from the ceiling of the room and connected to said furnace, a casing suspended from the ceiling of the room, a plurality of steam heated radiator sections within said casing connected to the furnace, means connected to the radiator sections and operated from a distance for causing the escape of air therefrom, a main hot air distributing pipe connected to one end of the casing, and a fan connected to the rear portion of the casing for forcing the heated air to the various rooms of the building.
4. A combined steam and hot air heating system for buildings comprising a hot air
- room provided with a hollow side wall having a series of inlets at its bottom for the admission of partially heated fresh air into said room, a steam boiler furnace within the room, a smoke flue heater connected to said furnace and suspended between the furnace and said wall, a steam coil heater suspended from the ceiling of the room and connected to the furnace, a casing suspended from the ceiling of the room, a plurality of steam heated radiator sections carried within said casing and connected with the furnace, an air moistener suspended within the casing and surrounding said radiator sections, said moistener being provided with a series of outlet openings, means connected with the radiator sections to freely permit the escape of air therefrom, a main hot air distributing pipe connected to the casing at one end of said casing, and a fan connected to the rear of the casing for forcing the heated air to the various rooms of the building.
5. A combined steam and hot air heating system for buildings comprising a hot air room provided with a hollow side wall having a series of inlets at its bottom for the admission of partially heated fresh air into the room, a steam boiler furnace within the room, a smoke flue heater connected to the furnace and suspended between said furnace and wall, a steam coil heater connected to said furnace and suspended from the ceiling of the room, a casing suspended from the ceiling of the room, a plurality of steam heated radiator sections carried within the casing and connected to the furnace, an air moistener suspended within the casing and surrounding said radiator sections, an air purifying and disinfecting tank connected with the outside of the furnace and provided with a series of outlet openings at its upper end portion, a main hot air distributing pipe connected with the casing at one end of said casing, and a fan connected to the rear portion of the casing for forcing the heated air to the various rooms of the building.

CHARLES R. HANSEN.
